(57) CLAIM

The ornamental design for a knife sharpener, as shown and described.

DESCRIPTION

FIG. 1 is a perspective view of a knife sharpener design showing my new design.

FIG. 2 is a front view of a knife sharpener.

FIG. 3 is a rear view of a knife sharpener.

FIG. 4 is a left side view of a knife sharpener.

FIG. 5 is a right side view of a knife sharpener.

FIG. 6 is a top view of a knife sharpener.

FIG. 7 is a bottom view of a knife sharpener; and,

FIG. 8 is a front, bottom side perspective view of a knife sharpener.

The broken lines depict portions of the knife sharpener in which the design is embodied that form no part of the claimed design.
